UNITED STATES PATENT OFFICE

WILLIAM LICHTENFELS, OF ORANGE, NEW JERSEY, ASSIGNOR TO GEMEX COMPANY,
A CORPORATION OF NEW JERSEY

BRACELET CHAIN

Application filed July 17, 1930. Serial No. 468,578.

This invention relates to a bracelet chain, and has for its object to provide a construction having the appearance of inner and outer series of links, the inner series being within 5 the outer series.

A further object of this invention is to provide a chain having open work for the circulation of air and in which each unit has an outer portion and an inner portion within it 10 similarly shaped and symmetrically disposed with relation thereto.

A still further object of the invention is to provide a connection between inner and outer portions of the unit which will be similar to 15 and present a symmetrical appearance with the connection between outer portions of the units, whereby an attractive appearance may be provided for the construction.

With these and other objects and advantages in view, the invention consists of a novel arrangement of parts more 20 fully disclosed in the detailed description following, in conjunction with the accompanying drawings, and more particularly set forth 25 in the appended claims.

In the drawings:

Fig. 1 is a top plan view of a pair of links connected together in hinged relation;

Fig. 2 is a bottom view thereof;

Fig. 3 is a section on line 3—3 of Figure 1;

Fig. 4 is a section on line 4—4 of Figure 1;

Fig. 5 is a perspective view of one of the units in which the inner and outer portions are formed in a single piece;

Fig. 6 is a top plan view of a modified construction in which the inner and outer parts of each unit are formed separate and connected together;

Fig. 7 is a bottom view of the structure shown in Figure 6; and

Fig. 8 is a section on line 8—8 of Figure 6.

Bracelet chains are formed with openings in the links, such links often being generally 45 rectangular in shape, and in order to provide a bracelet having the desirable features of the open-work bracelet for circulation of air about the arm or the like and yet provide a construction which will be stronger and of neat and varied appearance, I have formed 50 within each of the outer link portions an in-

ner link portion of generally the same shape and configuration and symmetrically disposed with relation to the outer portion, and have connected the longitudinally extending bars of the two links by cross bars, which are hinged together; and the following is a 55 detailed description of the present embodiment of this invention illustrating the preferred means by which these advantageous results may be accomplished.

With reference to the drawings, Figure 5 discloses a perspective view of one of the units which has outer bars 10 extending longitudinally of the chain and inner bars 11 60 similarly disposed and symmetrically arranged with reference thereto with spaces 12 between the inner and the outer bars. Cross bars 13 extend between the outer bars and are offset inwardly as at 14 to extend between and connect the inner bars 11 and provide a notch 28 for the purposes hereinafter 65 described.

These units are connected together by members 15 folded about and embracing adjacent bars 13 at spaced intervals, such as at each 70 side of the offset portion 14, and located in an opening 16 between the end of the inner bars 11 and the cross bar 13, to hingedly connect the units together. A member 17 is folded about each of the offset portions 14 in the 75 notch 28 to provide a similar appearance to the members 15 and cause the inner portion of the link to have the appearance of an inner chain within the outer chain to present a desirable effect for the bracelet.

The cross bar 13 and its offset portion 14 are of a thickness less than the thickness of the longitudinally extending bars 10 and 11, as is illustrated clearly in Figure 5, the thickness being substantially diminished by the 80 thickness of the stock of the members 15 or 17 which are folded about the cross bars to embrace the same, so that when completed, the tops of the members 15 and 17 lie flush 85 with the top surface of the bars 10, as illustrated clearly at 18 in Figure 4.

In some instances, I may form the chain of individual inner and outer links, as illustrated in Figures 6 and 7, the outer links 19 90 being complete within themselves, having 95 100

outer bars 20 connected by cross bars 21 at their ends, while the inner links are also complete, having longitudinally extending bars 22 connected by cross bars 23 at each of their ends. The bars 23 are connected to the bars 21 by members 24 at each end, while the bars 21 are hingedly connected to each other by connector members 25 at either side of the members 24, which members 25 may be connected together as illustrated by a web 26. The cross bars 21 are notched as at 27 to permit the members 24 to be inset thereinto and lie flush with the end surfaces of these cross bars in the same manner as the offset portion 14 forms a notch 28 for the reception of the member 17, heretofore described.

I have thus provided a chain in which each of the units consists of inner and outer members having the appearance when connected of two individual chains one within the other with each of the links symmetrically arranged one with the other.

While I have described certain construction forms which embody the principles of my invention, it is obvious that other desired changes in arrangement may be made within the spirit and the scope of the invention as defined in the appended claims.

I claim:

1. A bracelet chain comprising a series of units each comprising inner and outer portions, each having spaced parallel bars extending longitudinally of the bracelet to provide portions of two separately appearing links, the inner bars extending short of the outer bars, and means for hingedly connecting said units together.

2. A bracelet chain comprising a series of units each comprising spaced parallel bars extending longitudinally of the bracelet, the inner bars extending short of the outer bars, end bars joining both inner and outer bars, and means for hingedly connecting said units together.

3. A bracelet chain comprising a series of outer links of generally yoke-shape having longitudinally extending bars connected at their ends by cross bars, an inner link within each outer link of a similar shape and having longitudinally extending bars connected at their ends by cross bars, and means for hingedly connecting a series of outer links together.

4. A bracelet chain comprising a series of outer links of generally rectangular shape having longitudinally extending bars connected at their ends by cross bars, an inner link within each outer link of a similar shape and having longitudinally extending bars connected at their ends by cross bars, and means for connecting the cross bars of each series of links together.

5. A bracelet chain comprising a series of units each having spaced pairs of longitudinally extending bars with cross bars at their

ends and connecting members hingedly joining said units, and located in the spaces between said pairs of bars.

6. A bracelet chain comprising a series of units each having outer longitudinally extending bars and inner longitudinally extending bars with cross bars joining the same at their ends and connecting members between the outer and inner bars embracing the cross bars to hingedly join the units together.

7. A bracelet chain comprising a series of units each having outer longitudinally extending bars and inner longitudinally extending bars with cross bars joining the same at their ends, connecting members between the outer and inner bars embracing the cross bars to hingedly join the units together, said end cross bars being offset inwardly between the inner bars, and a member embracing each of said offset portions.

In testimony whereof I affix my signature.

WILLIAM LICHTENFELS.
